UNITED STATES PATENT OFFICE.

BASIL G. AUSTIN, OF HARTFORD, CONNECTICUT, ASSIGNOR TO AUSTIN ORGAN COMPANY, OF HARTFORD, CONNECTICUT, A CORPORATION OF MAINE.

PNEUMATIC ORGAN-ACTION.

1,277,529.

Specification of Letters Patent. Patented Sept. 3, 1918.

Application filed May 29, 1916. Serial No. 100,502.

To all whom it may concern:

Be it known that I, BASIL G. AUSTIN, a citizen of the United States, residing at Hartford, in the county of Hartford and 5 State of Connecticut, have invented certain new and useful Improvements in Pneumatic Organ-Actions, of which the following is a specification.

This invention relates to what I shall for 10 convenience term pneumatic organ action. The title adopted has been as noted, merely for convenience, although the mechanism is of particular advantage when incorporated in or forming part of a pipe organ; it is conceivable that it can be used with equal 15 utility in other connections. The action involves a relay which comprises a magnet-operated valve, and one of the points of the invention is the mounting and operation 20 of this valve in a simple and effective manner. In addition to the valve in question, there is a pneumatically-operated valve, and another object of the invention is the provision of a simple and inexpensive way of 25 mounting the cage in which this second valve is situated.

In the drawings accompanying and forming part of the present specification I have shown one convenient form of embodiment 30 of the invention which I will set forth fully in the following description. I do not however, restrict myself to this disclosure; I may depart therefrom in several respects within the scope of the invention defined 35 by the claims following said description.

Referring to said drawings:

Figure 1 is a transverse section of pneumatic organ action involving the invention.

Fig. 2 is an enlarged sectional view of the 40 magnet-operated valve and its adjuncts.

Fig. 3 is an inside face view of the casing for the magnet operated valve, and,

Fig. 4 is an outside face view of the cage for the pneumatically operated valve.

45 Like characters refer to like parts throughout the several views.

The relay mechanism comprises a main support as 2 and an auxiliary support as 3. Both these may as usual be of wood. The 50 main support 2 has certain windways, here-

inafter described, while the auxiliary support 3 constitutes what is known as a "relay bar". The two parts 2 and 3 are connected by parts as 4 having windways as 5. The part 3 can be held to the part 2, and the 55 connecting tubes 4 can be maintained in assembled relation with said parts 2 and 3 in some permanent manner as by screws 6. The support or bar 3 carries a number of cases as 7 generally made of metal. A detailed description of one case and its accessories will, of course, apply to the other, and for this purpose reference may be had especially to Figs. 2 and 3. The case therein shown has on its inner side near the upper 60 end thereof, the boss 8 adapted to snugly fit the passage 9, said case having near its lower end also on the inner side the projection 10 to fit the opening 11 in the relay bar 3. The case 7 is, therefore, removably 65 mounted. It is held in position by a spring 12 connected with the relay bar 3 and bearing against the cap or cover member 13 as will hereinafter more particularly appear. This cap or cover member 13 closes the outer 70 open side of the case 7, fitting a rabbet therein, the packing 15 conveniently of paper, resting on the bottom of the rabbet. It will be understood that the thin packing 15 has between its ends a slot 15' in constant 75 register with both the ports 18 and 19. This cover piece 13 constitutes a supporting member for the magnet 16 of horse-shoe type, the poles of the magnet being driven into holes in the said part 13. The free end of 80 the spring 12 to which I have already referred is fitted in an indentation 17 in the cover piece or supporting member 13. By disengaging the spring 12 from said part 13 the latter can be dismounted as can also the 85 case 7. In the cover piece 13 are ports 18 and 19. In the case 7 is an approximately oval flange 20, the space in which constitutes a port in register with the port 21 of the relay bar 3, said port 21 being in communication with the atmosphere. Adapted to seat against the outer edge of the oval flange 20 is the valve 22 constituting an armature for the magnet 16 and faced on its inner side as at 23 by leather or something of a 90 100

similar soft nature. The parts 2 and 3 and their adjuncts hereinbefore described are generally inclosed in a pressure box 2', the result being that when the magnet 16 is de-
5 energized, the pressure passing through the ports 18 and 19 closes the valve 22 against its seat as shown by full lines in Fig. 2.

The magnet 16 is normally deenergized. I have shown as connected with the terminals of the magnet the wires 25 and 26 constituting part of circuit connections which include a battery and a switch or other circuit-closing device. When the magnet is energized by the operation of the switch, 10 push button or the like, the valve 22, constituting an armature for the magnet is attracted by the magnet or moved to the open or dotted line position in said Fig. 2. It will be noted that the valve 22 is off center 15 with respect to the magnet 16, the longitudinal axis of said magnet being as shown above the center of the valve, the result being that the valve is initially given a tip or swinging movement and is thereafter 20 drawn bodily outwardly; so the valve is more efficiently and easily opened.

On the support or relay bar 3 is mounted a pneumatic 27 in communication with the port or passage 9 by way of the port 28. 25 The movable member of the pneumatic is connected with the stem 29 of the valve 30 mounted in the cage 31. This cage consists of a sheet metal shell covering the port or windway 32 leading from a pneumatic 30 (not shown). The valve 30 controls the port 33 which it is shown as closing in Fig. 1. The cage or elongated shell 31 has in its outer side the port 34 from which the annular flange 35 extends inward, the inner 35 edge of said flange constituting a seat for the valve 30. The port or windway 33 is in communication with atmosphere as is the port 36 into which the passage 5 hereinbefore described leads. The chamber 37 in 40 the relay bar 3 with which the passage or windway 5 communicates is also as will be obvious, in communication with the atmosphere. The shell 31 is merely fitted along the edge of its open side against the support 45 2; initially it may be held in position by a small quantity of shellac placed along said edge, although this is not always necessary, because it can be removably held in place merely by the use of the spring 38 50 55 (or equivalent means) of bowed form, one end of the spring being seated in the recess 39 in the upper edge of the relay bar 3, while the other end of the spring fits against the outer closed side of said cage or oblong shell 31. For holding the cage or shell 31 in proper relation, the pins 40 may be provided, these pins extending somewhat freely through perforations in the outer closed side of the cage and being driven into the sup-

port or bar 2. The spring 38 has an eye 60 at its inner end to fit over the upper of the two pins, by reason of which said upper pin aids in holding the spring in position. This provides an exceedingly simple way of holding the cage 31 in place. The use 70 of a valve as 30 and a valve as 22 and the hereinbefore described adjuncts thereof is in no sense new, the only novelty being in the manner in which the cage 31 is mounted, the way the spring 38 is associated with said. 75 case, and the novel relation between the valve 22 and its operating magnet 16 and certain details as will be more particularly set forth in my claims.

In Fig. 1 the parts are shown as occupying their normal positions, the valve 30 being closed against the inner end of the windway or port 33, while the valve 22 is closed against the port 20 as shown by full lines in Fig. 2. To obtain the pneumatic 80 action as familiar in organs, the magnet 16 will be energized to attract its armature 22 (constituting a valve) so as to cover the ports 18 and 19 to pressure and put the pneumatic 27 into communication with the 85 atmosphere. When this condition ensues, the pneumatic or bellows 27 will be collapsed so that the valve 30 will be drawn away from the port 33 and cover the port 34, so that the windway 32 will be put into connection with the port 33 by way of the cage 90 95 31 to effect the operation of the pneumatic or perform some equivalent act as quite common in organs.

When the magnet 16 is deenergized the 100 valve 22 is moved by the pressure in the pressure box against its seat on the flange 20 as shown by full lines in Fig. 2 thus cutting off the bellows or pneumatic 27 from the atmosphere and admitting pressure 105 owing to which the pressure can force the valve 30 against its seat at the inner end of the windway 33.

It will be noted that the side walls of the cage 31 and the pins 40 jointly act to 110 guide the valve 30. It will also be noticed that the packing 15 is free or loose, by reason of which it can be readily replaced if desired.

What I claim is:

1. The combination of a support having a port and a windway, a cage inclosing the windway and having a port, a valve in the cage to alternately close said ports, and a spring acting against the cage to hold the 120 same against said support.

2. The combination of a support having a port and a windway, a cage inclosing the windway and having a port, a valve in the cage to alternately close said ports, pins 125 extending freely through the cage and driven into said support, and a bowed spring bearing against the cage to hold the same

against said support, that part of the spring which holds the cage in place, having an eye to receive one of said pins.

3. The combination of a support having 5 a port and a windway, a cage inclosing the windway and having a port, a valve in the cage to alternately close said ports, and pins extending through the cage and into the sup-

port, the pins and the cage acting jointly to guide the valve. 10

In testimony whereof I affix my signature in presence of two witnesses.

BASIL G. AUSTIN.

Witnesses:

L. L. MARKEL,
HEATH SUTHERLAND.
